R. O. NELSON
By his Attorney
R. O. Nelson

UNITED STATES PATENT OFFICE.

ROBERT O. NELSON, OF SAN FRANCISCO, CALIFORNIA.

AUTO THEFT-PREVENTING DEVICE.

Application filed July 27, 1923. Serial No. 654,243.

To all whom it may concern:

Be it known that I, ROBERT O. NELSON, a citizen of the United States, residing at San Francisco, in the county of San Francisco and State of California, have invented certain new and useful Improvements in Auto Theft-Preventing Devices, of which the following is a specification.

This invention relates to theft-preventing means for motor vehicles, and the main object is to provide a simple, efficient and practical device for preventing the running of a vehicle motor and for informing officers and the public at large that an attempt is being made to steal the car when such an attempt is being made by an unauthorized person. Further and more specific objects will be disclosed in the course of the following specification, the invention being disclosed 20 in the accompanying drawing, wherein:

Fig. 1 is a fractional elevation of a motor car body showing the application of my invention thereto.

Fig. 2 is a view similar to Fig. 1, but showing the attached device partly in section and showing the sign plate in its extended position.

Fig. 3 is an enlarged section as seen on the line 3—3 in Fig. 1.

Fig. 4 is an enlarged section as seen on the line 4—4 in Fig. 2.

Fig. 5 is an end view of the device as it appears upon the outside of the car.

Referring to the drawing by reference characters 6 designates a sheath or casing, being open at one end, which end is secured in a suitable aperture in the car body 7. The casing may be arranged in any desirable place in the car, but is preferably secured under the windshield 8 and in back of the instrument or dash board of the car.

Slidably mounted in the casing 6 is a sign plate 9 on which is printed or otherwise impressed warning words of the character indicated in Fig. 2. The outer end of the plate is provided with a handle 10, and the inner end is provided with an upwardly projecting integrally formed arm 11. The upper edge of the plate is tubularly formed as at 12, and is therein provided with a rotatable rod 13, having a lateral projection or arm 14 at its inner end. The outer end of the rod 13 is connected to and is rotated by a key operated lock 15 inserted in the upper end of the handle member 10.

The upper part of the casing 6 is enlarged

by an inner channel portion 16, to accommodate the arm 14 when it moves back and forth when in the position indicated by dotted line 14^a in Figs. 3 and 4. The ends of said casing part are also enlarged as at 17 and 18, so that when the plate 9 and the rod 13 are in either extreme positions the latter can be rotated until the arm 14 is in either of the two positions indicated in Figs. 1, 2, 3 and 4. When locked in either of these two positions it is obvious that the plate 9 can not be moved.

A spring 19 within the casing 6 co-acts against the plate 9, when the latter is in its retracted or concealed position, and prevents the same from rattling or vibrating within the casing. When the plate 9 is extended (as in Fig. 2) a similar spring 20 acts against the arm 11 of the plate for the same purpose. To take up all loose play and to further effect rigidity to the plate 9, I provide a bar 21 in the upper part of the casing and near the arm 11. This bar is provided with an angular extension 22 which is engaged by the arm 11 when the plate 9 is pulled out into its extended position. The other end of the bar 21 is spring retained as at 23. Thus when the plate is exposed it is yieldingly resisted by the spring 23 and the bar 21, for the purpose above mentioned.

The bar 21 also functions as a circuit breaking means, it being connected by a link 24 to a switch lever 25, pivoted as at 26 in a small switch box 27. Ignition circuit wires 28 and 29, from the motor of the car, are connected, one with the lever 25 and the other to a terminal 30, which is touched by the lever 25, thus closing the circuit when the bar 21 is in its left-hand position, which will be when the sign plate 9 is concealed.

It will thus be readily understood that when the driver of the car is to leave the same and wishes to prevent tampering or stealing of the car when he is absent, he merely unlocks the lock 15 and pulls the plate 9 out, thus breaking the ignition circuit and exposing the sign, in which position the parts are locked until he returns and restores the parts to their normal and operative position.

It is further understood that suitable modifications may be made in the general design and structural details of the device as herein disclosed, provided, however, such modifications come within the spirit and scope of the appended claims.

Having now therefore fully shown and described my invention what I claim to be new and desire to protect by Letters Patent is:

5. 1. The combination with a motor vehicle, of a sign plate movable from a concealed to an exposed position, means operable by so moving the plate to break an ignition circuit, and means for locking the plate in said 10 exposed position.

2. A device of the class described consisting of a casing, a sign plate slidably mounted in the casing, a lock in the plate to lock it in concealed or extended positions with respect to the casing, and spring means engageable with the plate when the latter is concealed to prevent vibration thereof.

3. A device of the class described consisting of a casing, a sign plate slidably mounted in the casing, a lock in the plate to lock it in concealed or extended positions with respect

to the casing, and spring means for engaging the plate to prevent vibration thereof when in an extended position.

4. A device of the class described consisting of a casing, a sign plate slidably mounted in the casing, a lock in the plate to lock it in concealed or extended position with respect to the casing, a circuit switch, and means actuated by the plate to control said 30 circuit switch.

5. A device of the character described consisting of a casing, the same being open at one end, a sign plate slidable in the casing and extending through said end, a rod rotatable in the plate, said rod having an angular arm at its inner end and being rotatably controlled by a lock at its other end, and said casing having recesses at the ends thereof to receive the said rod arm.

In testimony whereof I affix my signature.

ROBERT O. NELSON.
